UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,697, dated May 2, 1899.

Application filed April 6, 1899. Serial No. 712,024. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part hereof, in which—

Figure 1 is a top or plan view of a manhole-cover embodying my design. Fig. 2 is a transverse section on the line $x-x$ of Fig. 1; and Fig. 3 is a diagonal cross-sectional view on the line $y-y$ of Fig. 1, these three views being deemed essential or necessary for a proper illustration and full understanding of the character of the design of my said invention.

The leading feature of my present design consists of the configuration or outline of the manhole-cover.

Referring to the drawings, the cover A when viewed in plan represents the appearance of an oblong and substantially square field a , provided with a slightly-inclined wall a' , terminating in a projecting rim a'' . The cover has a slightly-concave bottom a'' . From the lowermost portion of the concavity on the in-

ner side of the cover the wall surrounding the bottom is slightly convex or curved, as at a^4 , merging near the top in the rim portion into a concave niche or groove which extends along the sides and ends of the cover and terminating slightly below the top surface of the rim of the cover A. Diametrically opposite each other in the ends a^5 and a^6 are formed square-shaped recesses or offsets b and b' , as clearly shown in plan in Fig. 1. The outer corner-points c , c' , c^2 , and c^3 of the rim of the cover are slightly curved, as indicated in plan view in Fig. 1, and the inner edge of the rim about the four corners of the cover at d , d' , d^2 , and d^3 are curved, as clearly illustrated in Fig. 1 of the drawings.

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.
